Dec 1879

George B. Owen, of New York, N.Y.
Letters Patent No. 1879. Dated Jan 20th 1879.
Design for a Clock Case.

The schedule referred to in these Letters Patent and marking part of the same.

To all whom it may concern:

Be it known that I, George B. Owen, of the City, County and State of New York, have invented or produced a new and original Design for a Clock Case; and I do hereby declare that the following is a full, clear, and exact description of the same, reference being had to the accompanying drawings, making a part of this specification, in which,

Figure 1, is a front elevation of a clock case constructed according to my design.

Figure 2, a side elevation of the same.

Similar letters of reference indicate corresponding parts in the two figures.

This design for clock cases consists in having the top of the case formed with a double pitch and cornice, the front of the case being provided with pilasters having projecting ornaments, and the body of the case resting on a base provided with an inclined cap.

A, is the body or main portion of the clock case of quadrilateral form and having its top composed of two in

clined surfaces a, a, connected at their upper edges in line with the centre of the case, see Figure 1. The front edges of the inclined surfaces a, a, as well as the lower ends thereof project beyond the body A of the case and have an ornament formed on them, the same being composed of an ovoli b and b, a scotia c, an ovoli d, and a fillet e, and to the front of the body A of the case, and directly underneath the fillet e, there are attached at equal distances apart vertical rectangular blocks f, the lower ends of which are bevelled at their sides as shown at g. The blocks are of equal dimensions and in connection with the ornament at the front edges of the inclined surfaces a, a, form a cornice for the front of the case.

At each side of the front of the body A of the case there is a pilaster h, each having upon it an ornament i, in relief, formed of parallel sides j chamfered or bevelled at their front as shown at j; the tops of these ornaments are pointed as shown at k, and at their lower parts the bevelled edges j, are discontinued for a short space to form a nearly square panel l, see Figure 1.

The body A of the case rests on a base B of quadrilateral form and of rather larger dimensions than A to admit of an inclined cap C, at its upper end, said cap extending in front and at each side of the case.

What I claim as new and desire to secure by Letters Patent is,

The configuration and disposition of the parts herein shown and described to form a new and original design for a clock case.
